UNITED STATES PATENT OFFICE.

FRANK BURTT, OF KALAMAZOO, MICHIGAN, ASSIGNOR TO EVANSVILLE ARBOR PRESS COMPANY, OF EVANSVILLE, INDIANA.

MANDREL-PRESS.

1,356,905.

Specification of Letters Patent. Patented Oct. 26, 1920.

Application filed April 10, 1920. Serial No. 372,880.

To all whom it may concern:

Be it known that I, FRANK BURTT, a citizen of the United States, residing at Kalamazoo, county of Kalamazoo, State of Michigan, have invented certain new and useful Improvements in Mandrel-Presses, of which the following is a specification.

This invention relates to improvements in mandrel presses.

10 The main objects of this invention are:

First, to provide in a mandrel press an improved driving mechanism.

Second, to provide in a mandrel press an improved driving mechanism adapted for 15 driving the ram with great power for heavy work and with less power and greater speed for light work and for rapid adjustment to the work.

Third, to provide in a mandrel press an 20 improved ram.

Further objects, and objects relating to structural details, will definitely appear from the detailed description to follow.

I accomplish the objects of my invention 25 by the devices and means described in the following specification. The invention is clearly defined and pointed out in the claims.

A structure which is a preferred embodiment 30 of my invention is clearly illustrated in the accompanying drawing forming a part of this specification, in which:

Figure I is a front perspective view of a mandrel press embodying the features of 35 my invention, the actuating levers being partially broken away.

Fig. II is an enlarged detail vertical section on a line corresponding to line 2—2 of Fig. I.

40 Fig. III is an enlarged detail view partially in vertical section on a line corresponding to line 3—3 of Figs. II, IV and V.

Fig. IV is a detail view of the ram driving means partially in section on a line corresponding to line 4—4 of Figs. III and V.

Fig. V is a detail view partially in vertical section on a line corresponding to line 5—5 of Fig. III.

50 Fig. VI is a detail section on a line corresponding to line 6—6 of Figs. I and III showing details of the actuating means.

Fig. VI^A is a detail sectional view corre-

sponding to that of Fig. VI with the actuated lever in its forward or actuated position.

55

Fig. VII is an enlarged detail vertical section on a line corresponding to line 7—7 of Fig. I.

In the drawing similar reference characters refer to similar parts throughout the 60 several views, and the sectional views are taken looking in the direction of the little arrows at the ends of the section lines.

Referring to the drawing, the frame comprises a base 1, the uprights 2 and 3 and the 65 top plate 4. The uprights are disposed in a triangular position upon the base with the upright 3 at the rear. The top plate constitutes a support for the ram and its driving means and is provided with a gear housing 70 5. The lower portion 6 of the gear housing is, in the structure illustrated, formed integrally with the top plate 4.

The ram comprises a pair of ram members 7 each provided with a rack 8. These 75 ram members are disposed back to back through an opening 9 in the top plate 4. The top 10 of the gear housing 5 is provided with an opening 11 provided with a bearing bushing 12 for the ram.

80 At its lower end the ram is provided with a foot member 13 adapted to engage the work, the foot member embracing the lower ends of the ram members, as shown in Fig. VII, and being secured to one of them by a 85 lost motion connection, the foot member being slotted at 14 to receive the screw 15. Within the foot member is a compensating rocker 16 which receives the thrust of the ram members, permitting them to equalize 90 or adjust themselves and compensate for any variation in the racks or the driving connections or lost motion or back lash in the driving gears or looseness.

The driving shaft 17 is provided with a 95 driving pinion 18 meshing with a gear 19 on the driven shaft 20 disposed at one side of the ram. A second driven shaft 21 is disposed on the other side of the ram. These driven shafts 20 and 21 are provided with 100 pinions 22 meshing with the racks 8 of the ram. The driven shafts are connected by the gears 23 disposed at one side of the ram, the gear 19 being disposed at the other side

of the ram, thus providing a compact arrangement as shown in Figs. III, IV and V.

The driving shaft is provided with a pair of ratchet wheels 24 and 25. Mounted on the driving shaft between these ratchet wheels is a pawl carrier 26 having a pawl 27 thereon coacting with the inner ratchet wheel 24. Pivoted on this pawl carrier at 28 is an actuating lever 29 which is slotted at 30 to engage the pin 31 on the frame so that a very powerful operating means is provided.

To prevent the ram springing back, I provide a detent 32 which is pivoted at 33 to coact with the ratchet 24. This detent is provided with a rearwardly projecting arm 34 which is engaged by the rear weighted end 35 of the lever 29 when the lever is in its rear position thereby disengaging the detent, as shown in Fig. VI, and also disengaging the pawl 27, the detent being disposed so that it lifts the pawl when the detent is engaged by the lever.

To hold the detent in inoperative position, it is provided with a forwardly projecting arm 36 coacting with the cam-like keeper 37 which is provided with a finger piece 38 so that the keeper may be readily adjusted to hold the detent in inoperative position. A hand wheel 39 is provided for the rapid adjustment of the ram to the work.

To adapt the machine for light and rapid work I provide a second lever 40 which is mounted on the driving shaft and provided with a pawl 41 coacting with the ratchet wheel 25. This pawl is mounted directly on the lever to coact with the ratchet wheel. This provides means for rapid manipulations for light work, and further, the rapid actuating lever may be used to bring the work to a point where the more powerful lever is required and this results in great saving of time.

The table or work holder members 42 are pivoted on the frame uprights 2 and are provided with work holders 43 eccentrically curved on their inner edges so that by adjusting the table members on their pivots, the distance between the edges of the work holders is varied from their maximum to their minimum.

The bases 44 of the work holders rest upon the base 1 when the table members are swung to operative position so that a very rigid table or work support is provided and one fully adjustable to the work.

With this arrangement of parts I provide a press which is adapted for rapid work as well as work requiring great power. The compensating features of the ram greatly facilitate manufacture and relieves the gears of undue strains and stresses in operation.

I have illustrated and described my improvements in an embodiment which I have found very satisfactory. I have not at-

tempted to illustrate or describe certain modifications in structural details which I contemplate as being within the limits of the appended claims as I believe the disclosure made will enable those skilled in the art to which my invention relates to embody or adapt the same as may be desired.

Having thus described my invention, what I claim as new and desire to secure by Letters Patent, is:

1. In a mandrel press, the combination of a frame, a ram, a driving shaft, driving connections for said shaft to said ram, a pair of ratchet wheels mounted on said driving shaft, a pawl carrier journaled on said driving shaft between said ratchet wheels, a pawl on said pawl carrier coacting with the inner ratchet wheel, an actuating lever pivotally mounted on said pawl carrier and having a slot therein, a fulcrum pin on said frame engaged with said slot, a second actuating lever journaled on said driving shaft on the outer side of the outer ratchet wheel and provided with a pawl coacting therewith, a detent pivotally mounted on said frame to coact with said inner ratchet wheel, said detent being provided with forwardly and rearwardly projecting arms, said lever mounted on said pawl carrier being adapted to engage said rearwardly projecting detent arm when the lever is in its rear position whereby said detent is disengaged, and a keeper coacting with the forwardly projecting arm to hold said detent in operative position.

2. In a mandrel press, the combination of a frame, a ram, a driving shaft, driving connections for said shaft to said ram, a ratchet wheel mounted on said driving shaft, a pawl carrier journaled on said driving shaft, a pawl on said pawl carrier coacting with said ratchet wheel, an actuating lever pivotally mounted on said pawl carrier and having a slot therein, a fulcrum pin on said frame engaged with said slot, a detent pivotally mounted on said frame to coact with said inner ratchet wheel, said detent being provided with forwardly and rearwardly projecting arms, said lever being adapted to engage said rearwardly projecting detent arm when the lever is in its rear position whereby said detent is disengaged, and a keeper coacting with the forwardly projecting arm to hold said detent in inoperative position.

3. In a mandrel press, the combination of a frame, a ram, a driving shaft, driving connections for said shaft to said ram, a ratchet wheel mounted on said driving shaft, an actuating lever, a pawl coacting with said ratchet wheel actuated thereby, a detent pivotally mounted on said frame to coact with said ratchet wheel, said detent being provided with forwardly and rearwardly projecting arms, said lever being adapted to engage said rearwardly projecting detent arm

when the lever is in its rear position whereby said detent is disengaged and a keeper coacting with its forwardly projecting arm to hold said detent in inoperative position.

5 4. In a mandrel press, the combination of a frame, a ram comprising a pair of ram members disposed back to back and each provided with a rack, a foot embracing the lower ends of said ram members, a compensating rocker arranged in said foot member to receive the thrust of said ram members, a driving shaft, driving connections for said driving shaft to said ram comprising a pair of driven pinions meshing with said racks of said rack members, a ratchet wheel mounted on said driving shaft, an actuating lever, a pawl actuated thereby coacting with said ratchet wheel, a detent pivotally mounted on said frame to coact with said ratchet wheel, said lever being adapted to disengage said detent when in its rear position, and means for locking said detent in inoperative position.

5 5. In a mandrel press, the combination of a frame, a ram comprising a pair of ram members, a thrust compensating means for said ram members, a driving shaft, driving connections for said driving shaft to said ram members, a ratchet wheel mounted on said driving shaft, an actuating lever, a pawl actuated thereby coacting with said ratchet wheel, a detent coacting with said ratchet wheel, said lever being adapted to disengage said detent when in its rear position, and means for locking said detent in inoperative position.

6 6. In a mandrel press, the combination of a frame, a ram comprising a pair of ram members, a thrust compensating means for said ram members, a driving shaft, driving connections for said driving shaft to said ram members, a ratchet wheel mounted on said driving shaft, an actuating lever, a pawl actuated thereby coacting with said ratchet wheel, and a detent coacting with said ratchet wheel.

7 7. In a mandrel press, the combination of a frame, a ram comprising a plurality of driven ram members, a thrust compensating means for said ram members, a driving shaft, driving connections for said driving shaft to said ram members, a pair of ratchet wheels mounted on said driving shaft, a pawl carrier journaled on said driving shaft between said ratchet wheels, a pawl on said pawl carrier coacting with the inner ratchet wheel, an actuating lever pivotally mounted on said pawl carrier and having a slot therein, a fulcrum pin on said frame engaged with said slot, and a second actuating lever journaled on said driving shaft on the outer side of the outer ratchet wheel and provided with a pawl coacting therewith, all coacting for the purpose specified.

65 8. In a mandrel press, the combination

of a frame, a ram comprising a plurality of driven ram members, a thrust compensating means for said ram members, a driving shaft, driving connections for said driving shaft to said ram members, a pair of ratchet wheels mounted on said driving shaft, a pawl carrier journaled on said driving shaft, a pawl on said pawl carrier coacting with one of said ratchet wheels, an actuating lever pivotally mounted on said pawl carrier and having a slot therein, a fulcrum pin on said frame engaged with said slot, and a second actuating lever journaled on said driving shaft and provided with a pawl coacting with the other of said ratchet wheels.

9. In a mandrel press, the combination of a frame, a ram comprising a pair of ram members disposed back to back and each provided with a rack, a foot member embracing the lower ends of said ram members, a compensating rocker arranged in said foot member to receive the thrust of said ram members, a driving shaft disposed transversely of said ram and provided with a driving pinion, a pair of driven shafts disposed on opposite sides of said ram parallel to said driving shaft, pinions on said driven shafts meshing with the racks of said ram members, connecting gears for said driven shafts disposed at one side of said ram, and a gear on one of said driven shafts disposed in the other side of said ram and meshing with said pinion on said driving shaft.

10. In a mandrel press, the combination of a frame, a ram comprising a pair of ram members disposed back to back and each provided with a rack, a foot member embracing the lower ends of said ram members, a compensating rocker arranged in said foot member to receive the thrust of said ram members, a driving shaft disposed transversely of said ram and provided with a driving pinion, a pair of driven shafts disposed on opposite sides of said ram, pinions on said driven shafts meshing with the racks of said ram members, connecting gears for said driven shafts, and a gear on one of said driven shafts meshing with said pinion on said driving shaft.

11. In a mandrel press, the combination of a frame, a ram comprising a pair of ram members disposed back to back and each provided with a rack, a foot member embracing the lower ends of said ram members and having a lost motion connection to one of them, a compensating rocker arranged in said foot member to receive the thrust of said ram members, a driving shaft disposed transversely of said ram and provided with a driving pinion, a pair of driven shafts disposed on opposite sides of said ram, pinions on said driven shafts meshing with the racks of said ram members, connecting gears

for said driven shafts, and a gear on one of said driven shafts meshing with said pinion on said driving shaft.

12. In a mandrel press, the combination 5 of a frame, a ram comprising a pair of ram members disposed back to back and each provided with a rack, a thrust compensating means for said ram members, a driving shaft disposed transversely of said ram and 10 provided with a driving pinion, a pair of driven shafts disposed on opposite sides of said ram parallel to said driving shaft, pinions on said driven shafts meshing with the racks of said ram members, connecting gears 15 for said driven shafts disposed at one side of said ram, and a gear on one of said driven shafts disposed in the other side of said ram and meshing with said pinion on said driving shaft.
- 20 13. In a mandrel press, the combination of a frame, a ram comprising a pair of ram members disposed back to back and each provided with a rack, a thrust compensating means for said ram members, a driving shaft disposed transversely of said ram and 25 provided with a driving pinion, a pair of driven shafts disposed on opposite sides of said ram and provided with a driving pinion, a pair of driven shafts disposed on op- 30 posite sides of said ram, pinions on said driven shafts meshing with the racks of said ram members, connecting gears for said driven shafts, and a gear on one of said driven shafts meshing with said pinion on 35 said driving shaft.

14. In a mandrel press, the combination of a frame, a ram comprising a pair of ram

members disposed back to back and each pro- 40 vided with a rack, a foot member embracing the lower ends of said ram members and having a lost motion connection to one of them, a compensating rocker arranged in said foot member to receive the thrust of said ram members, and driving means for said ram comprising a pair of ram driving 45 gears meshing with said ram member racks.

15. In a mandrel press, the combination of a frame, a ram comprising a pair of ram members disposed back to back and each provided with a rack, a foot member em- 50 bracing the lower ends of said ram members, a compensating rocker arranged in said foot member to receive the thrust of said ram members, and driving means for said ram comprising a pair of ram driving gears 55 meshing with said ram member racks.

16. In a mandrel press, the combination of a frame, a ram comprising a plurality of driven ram members, a foot member, a com- 60 pensating rocker arranged on said foot member to receive the thrust of said ram members, and driving means for said ram members.

17. In a mandrel press, the combination of a frame, a ram comprising a plurality of 65 driven ram members, a thrust compensating means for said ram members, and driving means for said ram members.

In witness whereof I have hereunto set my hand and seal in the presence of a witness. 70

FRANK BURTT. [L.S.]

Witness:

LUELLA G. GREENFIELD.
